UNITED STATES PATENT OFFICE.

WILLIAM JOHNSON, OF HAMPSTEAD, NEW HAMPSHIRE.

MACHINE FOR CHAMFERING SOLES OF BOOTS AND SHOES.

Specification of Letters Patent No. 23,585, dated April 12, 1859.

To all whom it may concern:

Be it known that I, WILLIAM JOHNSON, of 5
Hampstead, in the county of Rockingham
and State of New Hampshire, have invented
an improvement in the tool for chamfering
soles for boots and shoes for which Letters
50 Patent of the United States numbered
21,760 were granted to me on the 12th day
of October, A. D. 1858; and I do hereby de-
clare that the same is fully described and
represented in the following specification and
the accompanying drawings, of which—

Figure 1, is a top view; Fig. 2, a front
elevation; Fig. 3, a rear elevation, and Fig.
15 4, a transverse section of my improved
chamfering tool.

Such tool as exhibited in the drawings
is composed of a knife holder A, a station-
ary edge bearer B, a sole rest C, a spring
20 presser D, and a knife F, the said knife be-
ing provided with a handle *h*, and inserted
with the knife holder and held in place
therein by a screw *a*. From the said knife
holder a lip *b*, extends upward at a right
25 angle, and has formed through it a curved
slot *c*, for the reception of a clamp screw *d*,
which extends through the said slot, and
into another such lip or carrier *f*, projecting
upward from and serving to support the
30 sole rest C, as well as the edge rest B.

In the chamfering tool as patented by me,
a handle was fastened directly to the sole
rest and extended outward therefrom at a
right angle to the knife and gave support
35 to the spring presser which also stood or
was arranged about at a right angle with
the knife edge.

In my present improved tool, I dispense
entirely with the said handle and in place
40 thereof extend the sole rest backward with
respect to the knife and its handle as shown
in the drawings or so as to enable me to ar-
range the spring presser about parallel to
the knife edge in a vertical direction as in-
45 dicated in the figures, the same causing the
spring presser to bear directly against or
upon the edge of the sole instead of at a

distance therefrom as it is likely to when
arranged as in my patented tool.

When the presser rests on the sole inside 50
of its edge, and not directly on the edge, the
edge of the sole is liable not to be reduced
to the desired thickness or to be unevenly
cut, but by making the presser stand at a
right angle to the direction of movement of 55
the knife while it may be cutting a sole, the
edge of the sole will be borne firmly down
upon the sole rest and will be evenly cut.
Besides, the presser is not likely to twist or
exert a torsion strain so as to affect the 60
proper adjustment of the knife with respect
to the sole and edge rests as it is likely to
in the arrangement of the spring presser as
shown in my patented chamfering tool.

The aforesaid new arrangement of the 65
presser and its rest or support C, with ref-
erence to the carrier *f*, and the knife holder
not only affords advantages in the action of
the presser on the sole, but enables me to
dispense with the handle projecting from 70
the presser support and to make use of the
knife handle *h*, as a means for holding the
whole instrument and moving it against a
sole. While my improved tool therefore pre-
serves the invention heretofore patented, 75
viz., a means not only of adjusting the an-
gular position of the knife with respect to
the sole rest, but the distance of the knife
therefrom at the edge gage, it contains an
important improvement in the arrangement 80
of the spring presser and the sole rest.

Therefore, I claim—

The improved chamfering tool or manu-
facture, as constructed with its sole rest and
presser arranged with respect to the carrier, 85
f, and the knife holder substantially as
shown in the accompanying drawings and
as hereinbefore specified.

In testimony whereof I have hereunto set
my signature.

WILLIAM JOHNSON.
